UNITED STATES PATENT OFFICE.

ISAAC KARPEN, OF CHICAGO, ILLINOIS, ASSIGNOR TO S. KARPEN & BROS., OF CHICAGO, ILLINOIS, A CORPORATION OF WEST VIRGINIA.

UPHOLSTERY-MACHINE.

No. 890,564.

Specification of Letters Patent.

Patented June 9, 1908.

Continuation of application Serial No. 341,584, dated November 1, 1906. This application filed August 24, 1907.
Serial No. 390,024.

To all whom it may concern:

Be it known that I, ISAAC KARPEN, a citizen of the United States, residing at Chicago, in the county of Cook and State of Illinois, 5 have invented a new and useful Improvement in Upholstery-Machines, of which the following is a specification.

My invention relates particularly to machines for use in forming upholstery pads, 10 such as are employed, for instance, in couch construction.

My present application is substituted for the one filed by me November 1, 1906, Serial 15 Number 341,584.

My primary object is to provide improved means for facilitating the application of the fasteners commonly employed for securing the fabrics, or coverings, of pads together at the edges of the pads.

The invention is usefully employed in connection with tufting-machines for facilitating the operation of finishing the edge-portions of the pads. In such connection, one or more edges of the follower, or presser-board, 25 of the tufting-machine are equipped with fastener-holders, comprising fastener-guides, or sockets, extending perpendicularly to the plane of the follower, the heads of the fasteners are received in said guides, and a pair 30 of removable retainer-rods are employed to hold the fasteners securely in their guides during the operation of stretching the fabric over the prongs of the fasteners, after which the fastener-prongs are bent over, or clenched; 35 and the retainer rods are then withdrawn to permit the follower to be lifted from the pad, the heads of the fasteners becoming thereby disengaged from the guides.

By preference, the mold of the tufting- 40 machine is of special construction, having removable edge-strips, or edge-rails, and means for stretching the outer covering (usually leather or imitation leather) over the bottom of the mold preparatory to adjusting the edge-strips and inserting the filling or padding material.

The invention is illustrated in its preferred embodiment in the accompanying drawings, in which:

Figure 1 represents a plan view of a tufting-machine with an upholstery pad in process of formation therein, the follower of the machine being provided at two of its edges with my improved fastener-holding devices and

the mold having provision at the corresponding edges for holding the margins of the fabric or leather covering during the filling, pressing and tufting operations, it being noted, also, that the inner (shown uppermost) fabric (usually canvas) is shown extending over the rail at the left-hand edge of the mold, according to the view shown in Fig. 2, and is shown folded back at the opposite edge of the mold, according to the view shown in Fig. 3; Figs. 2 and 3, broken sectional views taken as indicated at line 3 of Fig. 1, and illustrating different steps in the operation, as already indicated; Fig. 4, a broken edge-elevational view of the follower-board when equipped with my improved fastener-holding means; Fig. 5, a broken plan view of a vertically slotted metallic bar forming a portion of said fastener-holding means; Fig. 6, a broken view illustrating the manner of plaiting and perforating the leather to enable it to accommodate itself to the tufting and fastening operations; Fig. 7, a broken view of a leather fringe, or skirt, employed commonly in pad construction; Fig. 8, a view showing the manner in which the plies of the covering material and the fringe are joined together by the metallic fasteners employed; and Fig. 9, a perspective view of one of said fasteners.

In the illustrations, A represents a mold of a tufting-machine, said mold comprising a bottom *a* and removable edge-rails *a'*; B, a follower, or presser-board, serving to compress the pad within the mold in the usual manner; B¹, fastener-holders, or fastener-retainers, connected with two edges of the follower, and serving to hold the fasteners *b* during the tufting and fabric-fastening operations; and C, an upholstery pad in process of formation, and comprising an outer or top surface covering *c*, padding material *c'*, an inner or bottom covering *c''*, welts *c'''* (one shown), and fringes or flaps *c''''* (one shown), the coverings, the welt and the fringe being joined together, in the finished product, by fasteners in the manner illustrated in the upper right-hand portion of Fig. 1.

The bottom *a* of the mold is equipped in the usual manner with means for effecting tufting of the mattress or pad and enabling the tufting fasteners to be applied. The means for producing this result are not shown in detail, inasmuch as said means are well understood in the art. In the illustra-

tion given, the bottom a of the mold is equipped near two of its opposite edges with upwardly-projecting pins a^2 upon which the lateral margins of the top face covering of the 5 mattress or pad are impaled, said margins being preparatorily provided with perforations for receiving the impaling pins. The bottom member a of the mold is provided near the same edges with upwardly-projecting 10 dowel-pins a^3 which enter sockets or perforations a^4 with which the edge-rails a^1 are provided. The edge-rails a^1 of the mold are preferably provided at their inner sides with concave surfaces a^5 adapted to give the 15 desired conformation to the lateral edges of the pad or mattress.

The follower, or presser-board, B is provided with the usual perforations b^1 for enabling the tufting-fasteners b^2 to be applied 20 in the tufting operation. The follower is provided with perforations b^3 which fit over upwardly-projecting guide-pins b^4 with which the bottom a of the mold is provided near its end edges. These guides serve to 25 center the follower with relation to the mold. Each fastener-holder B^1 with which the follower B is equipped comprises a metal bar b^5 secured to a vertical edge of the follower and equipped with vertical T-shaped holder-slots b^6 ; and removable fastener-retaining bars or rods b^7 extending longitudinally of the bar b^5 and crossing the slots b^6 . The retainer-bars b^7 are entered in loop-form guides 30 b^8 extending vertically across the outer face of the bar b^5 . The bar b^5 is secured to the edge of the follower-board by means of screws b^9 . Each retainer-bar b^7 is equipped with a handle b^{10} and may be withdrawn by moving the bar longitudinally with relation 35 to the bar b^5 . The extremity b^{11} of each retainer-bar is preferably pointed to enable the bar to readily enter its guides. In use the retainer-bars b^7 are horizontally disposed and are separated from each other by a small 40 space b^{12} , said space being sufficient to receive the prongs b^{13} of the fasteners b . Each fastener b is provided with a head adapted to enter a T slot b^6 of the bar b^5 ; and the retainer-bars b^7 serve to securely hold the 45 fasteners in said slots during the operation of securing the edge-margins of the coverings of the pad or mattress together by means of the fasteners.

The pad or mattress C may or may not be 50 tufted, so far as my present invention is concerned. Where the tufting is desired the top face fabric c is provided at its lateral edge margins with groups of perforations c^6 , each group comprising three perforations so 55 arranged that when the covering material (usually leather) is plaited, as illustrated in Fig. 6, the perforations of each group are superposed and adapted to be received upon a single impaling pin.

60 In Figs. 2, 3 and 6 c^6 represents a plait of

the leather. It will be understood by those skilled in the art that the purpose of plaiting the leather is to enable the tufting to be effected, the plaits furnishing the necessary stock in the leather to enable the leather to 70 be pressed down into the filling of the mattress in a manner well understood. The tufting operation is greatly facilitated by stretching the leather upon the mold bottom in a plaited condition with the lateral margins of the leather impaled upon the pins a^2 . 75

In Fig. 2, c^7 represents a flap or margin which is provided at the lateral edge of the fabric c^2 for connection with the fasteners b ; and c^8 represents a similar flap or margin 80 adapted for connection with said fasteners. As shown in Fig. 7, the welt c^3 and the fringe c^4 are provided with registering perforations c^9 adapted to receive the prongs of the fasteners b .

85 From the foregoing description, the manner of forming the mattress or pad will readily be understood. Where the mattress is to be tufted the top face cover c is stretched, in plaited condition, upon the top surface of 90 the bottom of the mold with the outer face of the covering down, the lateral margins of the covering being impaled on the pins a^2 . The side-rails a^1 of the mold are then applied to the dowels a^3 . The padding material c^1 is 95 then filled in, the inner covering c^2 of the mattress is then laid over the padding material and the follower-board put in place and pressure applied. The tufting operation is performed in the usual manner, and the fasteners b are then inserted in the slot b^6 , the lower retainer-bars b^7 being first put in place and afterwards the upper retainer-bars being inserted to secure the fasteners firmly with their prongs pointing outward. The edge-rails a^1 are then removed, the flaps c^7 are turned upwardly and impaled upon the prongs of the fasteners, and the flaps c^8 of the covering c are then turned up and impaled upon the prongs. The fringe with the welt 100 connected therewith is then applied and the prongs of the fasteners bent, as illustrated in the upper right-hand portion of Fig. 1. The lower fastener retaining-bars are then withdrawn, thus enabling the follower-board to 105 be lifted from the mold. The pad or mattress may then be lifted from the mold, inverted and applied to a couch, or to any article of furniture to which it is to be applied. In couch construction, the fringes c^4 110 are turned outwardly after the pad is applied to the frame of the couch, and are then secured to the side-rails of the couch.

115 It will be obvious that while I have shown a follower-board equipped at only two of its 120 edges with fastener-holders, said fastener-holders may be applied to as many of the edges of the follower as desired. The advantage of being able to connect the edges of the pad coverings while the pad is still in 125 130

the mold of a tufting-machine, will at once be evident to those skilled in the art. It likewise will be evident that this advantage will be present whether the mold be equipped 5 with means for performing the tufting operation or not, the essence of the leading feature of my invention lying in providing a follower, or presser-member, of a mold with fastener-holding means, on the principle set forth.

It may be added that while I prefer to employ the fastener-guides perpendicular to the edge of the follower-board, which permits the board to be lifted directly from the pad, and 10 the withdrawable retainer-rods crossing all the fastener-guides of each series, still these attributes of the invention are not to be regarded as indispensable. The fastener-guides may extend in any desired direction 15 with relation to the edge of the follower-board, and any suitable expedient may be adopted for maintaining the holders in their guides until it is desired to remove the follower-board from the pad. For instance, 20 in some cases, the retainer-rods may be dispensed with and the frictional contact of the fasteners with their guides depended upon to hold the fasteners in place until force is applied to remove the follower-board from the 25 pad; or, individual retainers for the fasteners may be provided. The fastener-guides themselves may be formed and applied to the follower-board in any suitable manner.

The foregoing detailed description has 30 been given for clearness of understanding only, and no undue limitation is to be understood therefrom.

What I regard as new, and desire to secure by Letters Patent, is:

40 1. The combination with a presser-member in a pad-forming machine of a fastener-holder having fastener-guides therein, and a withdrawable fastener-retaining bar crossing said guides.

45 2. The combination with a presser-member in a pad-forming machine, of a series of guide-slots at one edge of said member, and a retainer-bar crossing said guide slots.

3. The combination with a presser-element in a mattress-forming machine, of a series of fastener-guides extending across an edge of said element, and a pair of withdrawable retainer-bars crossing said guides.

4. The combination with a follower-board 50 in a mattress-forming machine, of fastener-holding means, comprising a bar applied to one edge of the follower-board and provided with a series of transverse fastener-guides, and retainers extending across said fastener-guides for locking the fasteners therein, for the purpose set forth.

5. In means of the character set forth, the combination with a presser-member, of fastener-holding means applied to one edge 55 thereof, comprising a member provided with

a series of transverse fastener-guides, and a pair of withdrawable retainer-bars connected with said second-named member serving to lock the fasteners in said guides.

6. In a machine of the character set forth, 70 the combination with a follower-board, of fastener-holding means comprising a bar applied to one edge of said board and equipped with a series of transverse guides, retainer-bar guides connected with said first-named bar, and a pair of withdrawable retainer-bars in said last-named guides, said retainer-bars being separated by a space sufficient to receive the prongs of fasteners.

7. The combination of a mold having a 80 bottom equipped at opposite edges with impaling pins, removable edge-rails connected with said bottom, and a follower-board equipped at opposite edges with fastener-holding means.

8. The combination with a follower-board equipped at opposite edges with fastener-holding means, of a mold comprising a bottom equipped at opposite edges with upwardly-extending impaling pins, and a pair 90 of removable edge-rails supported on the upper surface of said bottom, for the purpose set forth.

9. Fastener-holding means for the purpose set forth, comprising a bar equipped with 95 transverse fastener-guides for receiving the headed portions of fasteners, and a withdrawable retainer-bar extending longitudinally of said first-named bar and crossing said guides.

10. The combination with a presser-member in a pad-forming machine, of fastener-holding means applied to an edge thereof and adapted to hold fasteners with their prongs projecting from the edge of the presser-member, whereby the flaps of the upper and lower coverings and of the fringe may be impaled upon the prongs of the fasteners and said prongs bent into holding position before the pad is removed from the mold, as set forth.

11. The combination with the follower-board of a tufting-machine, of fastener-guides at the edges of the follower-board having channels for the heads of fasteners and channels through which the prongs of the fasteners may project from the edge of the board, whereby the flaps of the upper and lower coverings and of the fringe may be impaled upon the prongs of the fasteners and said prongs bent into holding position before the pad is removed from the mold, as set forth.

12. The combination with a presser-member in a pad-forming machine, of fastener-guides at an edge thereof extending substantially perpendicular to the plane of said presser-member, whereby the flaps of the upper and lower coverings and of the fringe may be impaled upon the prongs of the fasteners and said prongs bent into holding posi-

tion before the pad is removed from the mold, as set forth.

13. Fastener-holding means for the general purpose set forth, comprising fastener-guides with means for applying them to the edges of a presser-member, said fastener-guides having channels for the fastener-heads which extend substantially perpendicular to the plane of the presser-member and 10 channels intersecting said first-named chan-

nels, through which the prongs of the fasteners may project from the edges of said presser-member, whereby the presser-member may be lifted from the pad, after the fasteners held by said guides are clenched.

ISAAC KARPEN.

In presence of—

L. HEISLAR,

R. SCHAEFER.
